UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

THREAD CONTROLLER FOR SEWING MACHINES.

Application filed August 23, 1926. Serial No. 130,954.

The invention relates to new and useful improvements in thread controllers for sewing machines, and more particularly to a rotary thread controller which is especially 5 adapted for use in connection with the looper thread of a locked chain stitch sewing machine.

An object of the invention is to provide a thread controller for sewing machines including an annular member of uniform diameter and having a cam-shaped peripheral edge and cooperating thread guides, one located within and one without said peripheral edge, which can be mounted on a shaft intermediate the ends thereof without any liability of the thread controlled thereby being wound on to the shaft.

A further object of the invention is to provide a thread controller of the above type 20 wherein said guides are so mounted that they can be readily moved to a more accessible point for threading.

A further object of the invention is to provide a controller of the above type wherein 25 the thread controlled is positively carried forward in a circumferential direction by a controlling cam.

A further object of the invention is to provide a thread controller of the above type 30 wherein the thread controlled thereby is released at times, and after it is released, a frictional drag is placed thereon to prevent the thread from being given up too rapidly.

A still further object of the invention is to 35 provide a thread controller of the above type having a thread retaining finger which is adjustable in an axial direction relative to the rotatable controller and also circumferentially of the thread controller.

These and other objects will in part be 40 obvious and will in part be hereinafter more fully disclosed.

In the drawings which show by way of 45 illustration one embodiment of the invention—

Figure 1 is a view partly in section and partly in front elevation showing a portion of a sewing machine having my improved thread controlling mechanism embodied 50 therein;

Fig. 2 is a view partly in plan and partly in section of the parts below the cloth plate of the sewing machine, and showing the

thread controlling mechanism in top plan view;

Fig. 3 is an enlarged sectional view showing the thread controller with the rotating thread controlling element in end elevation;

Fig. 4 is an enlarged sectional view showing the rotatable thread controller and the parts directly associated therewith as viewed from the opposite side of that shown in Fig. 3;

Fig. 5 is a sectional view on the line 5—5 of Fig. 4;

Fig. 6 is a view more or less diagrammatic showing the thread controller as having taken up the looper thread and holding the same to aid in forming the triangle in the looper thread for the needles to enter;

Fig. 7 is a view similar to Fig. 6, but showing the thread controller as operating to take up or hold the looper thread during the forward movement of the looper;

Fig. 8 is a view similar to Fig. 7, but showing the looper thread as retained by the frictional drag thereon, and given to the loopers during their forward movement into the needle thread loops;

Fig. 9 is a sectional view on the line 9, 9 of Fig. 8;

Fig. 10 is a perspective view of a supporting sleeve carrying the cast-off and retainer, and

Fig. 11 is a perspective view of the rod in which the thread guides are formed.

The invention is directed broadly to a thread controller for sewing machines, and more particularly to a thread controller which is especially adapted for controlling the looper thread in a locked chain stitch machine. This thread controller is of the type shown in my prior patent application Serial No. 715,421, filed May 23, 1924, and the broad invention is claimed therein. The thread controller includes a rotating annular member of uniform diameter and having a cam-shaped peripheral edge. Preferably, there are two annular cams, one within the other. The rotatable controlling element in the present embodiment of the invention is mounted on a rotating shaft intermediate the ends thereof. On the shaft on which the controlling element is mounted is a sleeve which is fixed against rotation, and this sleeve extends into

the cylindrical or annular rotating member

so that the peripheral cam edge of said controlling member overhangs the stationary sleeve. This is for the purpose of preventing the thread from being caught by any rotating parts of the shaft on which the controlling cam is mounted, and wound thereon. Also mounted on this stationary sleeve and associated with the rotatable controlling element is a bracket carrying a cast-off member and 10 a retaining finger. This cast-off member is so shaped, that the thread during the rotation of said controlling element is positively carried forward in a circumferential direction by the rotation of the controlling element. During the forward movement of the thread, it is also moved axially of the controlling element to a point where it is cast off from the take-up cam of the controlling element. There are thread guides located, 20 one without the periphery and the other within the periphery of the rotating controlling element, as in my prior application. The retaining finger is adjustably mounted in the stationary sleeve. The controlling element 25 is so positioned relatively to this retaining finger that when the thread is cast off from the take-up cam, a frictional drag will be placed thereon so that the thread will not be given up too rapidly. The retaining finger 30 is capable of adjustment for varying the frictional drag, and so as to accommodate threads of different sizes. The controlling element is also provided with a notch in its peripheral edge so as to provide for a second taking up 35 of the thread during the rotation of the controlling element.

Referring more in detail to the drawings, I have shown my thread controlling mechanism as used in connection with the controlling of the looper thread in a sewing machine. The sewing machine consists of a bed plate 1 having an overhanging arm 2 carrying a needle head 3 in which reciprocates a needle bar 4 carrying needles 5 and 6. These needles are set in a line inclined to the line of feed, and there is a threaded looper cooperating with each needle. The looper 7 cooperates with the needle 5, and the looper 8 cooperates with the needle 6. These thread carrying loopers are mounted on a looper carrier 9 pivoted at 10 to a looper support 11. The looper carrier is oscillated on the support by a link 12, and the looper support is oscillated by an arm 13 cooperating with an eccentric on the main shaft 14. These parts are all of the usual construction. The thread controlling mechanism consists of a rotating cylindrical or annular member 15. This controlling member 15 consists of a hub portion 16 on which is formed an integral disk 17. At the outer edge of the disk 17 is a cylindrical or flange portion 18, and spaced from this outer flange portion 18 is a similar flange portion 19. The flange portion 18 is of uniform diameter throughout the entire circum-

ference of the controlling member, and likewise the flange member 19 is of uniform diameter throughout its entire circumference, although the diameter, of course, of the flange member 18 is greater than the diameter of the flange member 19. This provides an annular space 20 in which is located the cast-off member and a portion of the retaining finger.

The controlling member 15 is mounted on the main shaft 14 and is secured thereto by a set screw 21 which is located in the hub 16. Mounted on the main shaft 14 is a sleeve 22. This sleeve 22 is provided with a recess at the right-hand end thereof as shown in Fig. 5 which receives the hub of the controlling member 15. The hub is entirely housed within this recess, and the set screw 21 is completely covered by the sleeve. The sleeve 22 makes a very loose fit with the shaft 14 and is held from rotation by a pin 23 which is fixed to the bed plate 1 and extends into an opening in the sleeve 22.

Mounted on the sleeve 22 is a bracket 24. Said bracket 24 is attached to a clamp collar 25 which is clamped to the sleeve 22. This collar is capable of being shifted endwise of the sleeve and also circumferentially on the sleeve when the clamping screw for the collar is released. A clamping screw is indicated at 26 in Fig. 4 of the drawings. The bracket 24, at its outer end, carries a cast-off member 27 and a retaining finger 28. The cast-off member and the retaining finger are curved to conform to the curvature of the annular portion of the controlling member, and these parts extend into the annular space 20 between the annular controlling cams.

The thread of the looper 7 is indicated at 29 in the drawings, while the thread of the looper 8 is indicated at 30. These threads pass from the supply through suitable tensions and thence through suitable thread guides 31. The threads pass underneath a guiding wire 32, thence over a portion of the same wire and along opposite sides of a guiding post 33. From this point, the threads pass underneath nipper springs 34, and thence to the thread eye 35 located within the periphery of the annular controlling element. After leaving the thread eye 35, the threads are lead to the thread eyes 36, 36, and through the thread eyes 36, 36 to their respective loopers. The thread eyes 35 and 36 are formed in a supporting arm 37. The thread eyes 36 are located outside of the peripheral edge of the controlling element, while the thread eyes 35 are inside the peripheral edge of the controlling element as stated above. The thread controlling element is provided with a take-up cam 38 formed by cutting away the cylindrical portion of the controlling element. The arm in which the thread eyes 35 and 36 are formed is bent inwardly and thence back on itself, so that the thread eyes are well underneath the cylindrical portion of the

thread controlling element at all points in the circumference thereof, except at the main cut away portion which forms the main take-up cam 38. This cut away portion is of sufficient size as to permit the raising of the inner guide. The arm 37 has a right-angled portion 39 which is mounted in a recess 40 in a bracket 41 secured to the bed plate 1 of the machine. This angular portion 39 is provided with an offset 42. A spring 43 carried by the bracket 41 bears against this offset and will retain the arm either in horizontal position or in raised position. When in its horizontal position, the arm rests on an adjustable screw 44, and this determines the position of the arm relative to the rotatable thread controlling element. When the machine is threaded, the arm is raised so that the thread eyes are accessible for threading and the arm can be readily raised by turning the main shaft so as to bring the cut away space directly above the inner end of the arm 37 in which the thread eyes 35 are formed.

The cylindrical portions of the thread controlling element 15 are not only cut away to form the take-up cam 38, but are also cut away to form a take-up shoulder 45. The inner edge of the retaining finger 28 is within the peripheral edges of the cylindrical portions, but said retaining finger is of such thickness and is so positioned that the thread can slide along between the retainer and the edge of the cylindrical portion and can be taken up for use without the rapid giving up of the thread. The take-up cam 38 is formed by the inclined edge of the cylindrical members, and these inclined edges terminate in more or less of a sharp shoulder 38^a. The inclined face of the cast-off member 27 terminates in a notch 27^a which is disposed at the outer side of the extreme lateral edge of the cylindrical members of the rotating controlling member.

The construction of the rotating controlling element and the parts associated therewith will probably be best understood by a description of the method of operation. The take-up cam 38 comes into engagement with the looper threads between the thread eyes 35 and 36 when the looper is on its rethreading movement. It is at this time that the looper thread should be drawn taut in order that the thread running from the eye of the looper to the previous stitch will be held substantially taut and insure the needle entering its proper thread triangle formed by the looper thread just referred to, the body of the looper and the needle thread loop which is, at this time, on the looper. The take-up cam 38 engaging the looper threads carries them against the inclined face of the cast-off member 27, the threads will ride along this inclined edge and also along the inclined edge of the take-up cam 38 until the threads reach the shoulder 38^a, and they will be carried by the shoulder

38^a to a point where they are cast off into the notch 27^a. It will be noted that the notch 27^a is at a considerable distance circumferentially of the rotating controlling element from the thread eyes 35 and 36. Therefore, 76 the thread as it is carried forward and cast off into this notch, will be carried mainly in a circumferential direction of the thread controlling element. It will be carried to a certain extent axially of the thread controlling 75 element so that it can be cast off. This circumferential movement of the thread relative to the thread controlling element enables a considerable quantity of thread to be taken up without having an excessive overhang of 80 the cylindrical portions of the controlling element.

After the loopers leave the needle thread loops, the thread is held under gentle frictional drag control upon the moving straight 85 edges of the controlling element and the retaining fingers 28. Just as the looper stops on its rearward movement, the shoulder 45 formed by cutting away the peripheral edge 90 of the shell members of the rotating controlling element, moving along the retaining finger 28, will take up the looper threads and carry them back up into the notch 27^a. Thus it is that the looper thread is drawn back through the looper or held from movement 95 forward, in front of the looper so that the looper will slide along the looper thread until the looper point reaches and enters the needle thread loop. This prevents slack thread from forming in front of the point of the looper 100 which might force the needle thread loop to one side and cause a skipping of stitches. After the looper point is well into the needle thread loop, then the shoulder 45 coming opposite the notch 27^a will release the looper 105 thread and the looper thread will be merely held by the frictional drag of the retaining finger on the looper thread. The looper moving on to the forward end of its stroke requires thread to form its thread loop, and this is given up to the looper by the looper thread sliding along the straight peripheral edge of the rotating controlling element, but subject to the frictional drag so that it is not given up too rapidly. Of course, when the 110 space in the cut away shell reaches the retaining finger, then the thread will be entirely released and may be drawn to a position substantially straight from the thread eye 35 to the thread eye 36.

By loosening the clamping sleeve supporting the bracket 24, the thread retaining finger can be shifted so as to vary the frictional drag on the looper thread, or so as to accommodate different sized threads. The cast-off member 115 can also be adjusted circumferentially of the operating shaft by loosening the clamping sleeve. This adjustment permits the changing of the time of the casting off of the thread to suit different conditions in the machine. In- 120 125 130

asmuch as the sleeve 22 is stationary, there is no possible chance of the looper thread being wound up on to the shaft 14 or the inner parts of the rotating thread controlling element.

While I have described the rotating thread controlling element as mounted on the shaft adjacent the bed plate of the machine, it will be understood, of course, that this thread controlling element may be mounted on a top shaft in other types of machines. It must be mounted, of course, on a rotating shaft, but this rotating shaft may be selected or positioned at any desired point in the machine.

While I have described the thread controlling mechanism as particularly adapted for controlling the looper thread of a locked chain stitch machine, it will be understood that it may also be used for other types of machines, and for controlling the needle thread, as I believe I am the first to develop a thread controlling mechanism wherein the thread is controlled by a rotating annular cam, with guides for the thread positioned within and without the peripheral portions of the controlling cam where said thread controlling cam is mounted on a shaft intermediate the ends thereof.

It is obvious that minor changes in the details of construction and the arrangement of the parts may be made without departing from the spirit of the invention as set forth in the appended claims.

Having thus described the invention, what I claim as new and desire to secure by Letters-Patent, is—

1. The combination of a shaft, a thread controlling member mounted on said shaft and having a laterally projecting thread engaging surface overhanging said shaft, thread guides located one within and one without the periphery of said thread engaging surface for guiding the thread for engagement therewith, said thread engaging surface being in part cam-shaped and in part straight relative to its path of travel, a stationary cast-off finger adapted to be engaged by the thread on the cam-shaped surface for forcing the same laterally off from said surface, and a retainer finger parallel with the straight edge of the controlling member for placing a frictional drag on the thread as it passes along said straight edge.

2. The combination of a shaft, a disc fixed to said shaft and having a laterally projecting cylindrical flange, said flange being cut away in part at its outer edge to form a thread controlling cam, thread guides, one within and one without said flange, a stationary member extending beneath said flange to a point adjacent the disc, and a stationary cast-off member mounted on said stationary member and associated with said flange for moving the thread off from said cam.

3. The combination of a shaft, a disc fixed to said shaft and having a laterally projecting cylindrical flange, said flange being cut away in part at its outer edge to form a thread controlling cam, thread guides, one within and one without said flange, a stationary member extending beneath said flange to a point adjacent the disc, a cast-off member associated with said flange for moving the thread off from said cam, and a retaining finger for putting a frictional drag on the thread when released from the cam, said cast-off member and said retaining finger being mounted on said stationary member.

4. The combination of a shaft, a disc fixed to said shaft and having a laterally projecting cylindrical flange, said flange being cut away in part at its outer edge to form a thread controlling cam, thread guides, one within and one without said flange, a stationary member extending beneath said flange to a point adjacent the disc, and a cast-off member mounted on said stationary member and associated with said flange for moving the thread off from said cam, said flange having a second cut-away portion for engaging and taking up the thread a second time during the rotation of the shaft.

5. The combination of a shaft, a disc fixed to said shaft and having a laterally projecting cylindrical flange, said flange being cut away in part at its outer edge to form a thread take-up cam, thread guides, one within and one without said flange, and a stationary cast-off member and a stationary retaining finger associated with said flange, said finger being located along the outer edge of the flange and spaced therefrom so as to put a frictional drag on the thread when released from said cam.

6. The combination of a shaft, a disc fixed to said shaft and having a laterally projecting cylindrical flange, said flange being cut away in part at its outer edge to form a thread take-up cam, thread guides, one within and one without said flange, a stationary cast off member, a stationary retaining finger associated with said flange, said finger being located along the outer edge of the flange and spaced therefrom so as to put a frictional drag on the thread when released from said cam, and means for adjusting the finger toward or away from said flange.

7. The combination of a shaft, a disc fixed to said shaft and having a laterally projecting cylindrical flange, said flange being cut away in part at its outer edge to form a thread take-up cam, thread guides, one within and one without said flange, a stationary cast-off member and a stationary retaining finger associated with said flange, said finger being located along the outer edge of the flange and spaced therefrom so as to put a frictional drag on the thread when released from said

cam, a bracket for supporting said cast-off member and said retaining finger, said bracket having a notch at the base of the retaining finger into which the thread is cast and momentarily held before it passes along said finger.

8. The combination of a shaft, a disc fixed to said shaft and having parallel spaced laterally projecting flanges, said flanges being 10 cut away in part at their outer edges to form annular thread take-up cams, thread guides, one within and one without said flanges and disposed so as to hold the thread for engagement with said cams, a stationary cast-off 15 member extending into the space between said flanges, a stationary retaining finger extending into the space between said flanges and having its edge adjacent the flanges substantially parallel to and spaced from the 20 edges of the flanges so that a frictional drag is placed on the thread after it is released from the take-up cams.

9. The combination of a shaft, a disc fixed to said shaft and having parallel spaced laterally projecting flanges, said flanges being 25 cut away in part at their outer edges to form annular thread take-up cams, thread guides, one within and one without said flanges and disposed so as to hold the thread for engagement with said cams, a stationary cast-off 30 member extending into the space between said flanges, a stationary retaining finger extending into the space between said flanges and having its edge adjacent the flanges substantially parallel to and spaced from the edges 35 of the flanges so that a frictional drag is placed on the thread after it is released from the take-up cams, said disc being so disposed on the shaft that the flanges overhang the 40 shaft, and a stationary member extending beneath the flanges to a point adjacent said disc and all the way around said shaft so as to prevent the thread from catching and winding on said shaft.

45 10. The combination of a shaft, a disc, a hub carrying said disc and secured on said shaft, said disc having a laterally projecting cylindrical flange cut away at its outer edge to form a thread controlling cam surface, 50 thread guides, one within and one without said flange, a stationary cast-off member associated with said flange, said disc being so disposed on said shaft that the flange overhangs the shaft, and a sleeve loosely mounted 55 on said shaft and extending beneath said flange, and means to hold said sleeve stationary.

11. The combination of a shaft, a disc, a hub carrying said disc and secured on said 60 shaft, said disc having a laterally projecting cylindrical flange cut away at its outer edge to form a thread controlling cam surface, thread guides, one within and one without said flange, a stationary cast-off member associated with said flange, said disc being so

disposed on said shaft that the flange overhangs the shaft, a sleeve loosely mounted on said shaft and extending beneath said flange, and means to hold said sleeve stationary, said sleeve having a recess formed in its inner end 70 adapted to extend over and house said hub.

12. The combination of a shaft, a disc, a hub carrying said disc and secured on said shaft, said disc having a laterally projecting cylindrical flange cut away at its outer edge 75 to form a thread controlling cam surface, thread guides, one within and one without said flange, a stationary cast-off member associated with said flange, said disc being so disposed on said shaft that the flange overhangs the shaft, a sleeve loosely mounted on said shaft and extending beneath said flange, means to hold said sleeve stationary, said sleeve having a recess formed in its inner end 80 adapted to extend over and house said hub, and a retaining finger mounted on said sleeve and extending along the outer edge of said flange for placing a frictional drag on the thread when released from said cam.

13. The combination of a shaft, a disc, a hub carrying said disc and secured on said shaft, said disc having a laterally projecting cylindrical flange cut away at its outer edge to form a thread controlling cam surface, 90 thread guides, one within and one without said flange, a stationary cast-off member associated with said flange, said disc being so disposed on said shaft that the flange overhangs the shaft, a sleeve loosely mounted on said shaft and extending beneath said flange, 95 means to hold said sleeve stationary, said sleeve having a recess formed in its inner end adapted to extend over and house said hub, a retaining finger mounted on said sleeve and extending along the outer edge of said flange for placing a frictional drag on the thread when released from said cam, and means whereby said finger can be shifted endwise of said sleeve. 100

14. The combination of a shaft, a disc secured to said shaft and having cylindrical flanges projecting laterally therefrom, said flanges being cut away in part to form thread controlling surfaces, thread guides located one within and one without said flanges, an arm carrying said guides, and means for supporting said arm whereby when said cut away portions of the flanges are over said inner guide, said arm can be raised and the guides positioned for threading. 110

15. The combination of a shaft, a disc fixed to said shaft and having a laterally projecting cylindrical flange, said flange being cut away in part at its outer edge to form a thread take-up cam, thread guides, one within and one without said flange, a stationary cast-off member, and means for adjusting said cast-off member circumferentially of said shaft. 125

16. The combination of a shaft, a thread 130

controlling member mounted on said shaft intermediate the ends thereof and having a laterally projecting thread engaging surface, thread guides located one between the periphery of said thread engaging surface and the shaft and the other outside of said periphery for guiding the thread for engagement with said thread engaging surface.

17. The combination of a shaft, a thread controlling member mounted on said shaft intermediate the ends thereof and having a laterally projecting thread engaging surface, thread guides located one between the periphery of said thread engaging surface and the shaft and the other outside of said periphery for guiding the thread for engagement with said thread engaging surface, and a stationary sleeve encircling said shaft and extending beneath the thread engaging surface so as to prevent a loose end of thread from catching and winding on said shaft.

18. The combination of a shaft, a thread controlling member mounted on said shaft intermediate the ends thereof and having a laterally projecting thread engaging surface, thread guides located one between the per-

iphery of said thread engaging surface and the shaft and the other outside of said periphery for guiding the thread for engagement with said thread engaging surface, a stationary sleeve encircling said shaft and extending beneath the thread engaging surface so as to prevent a loose end of thread from catching and winding on said shaft, and a cast-off member and a retaining finger mounted on said stationary sleeve and cooperating with said thread engaging surface for casting the thread off from said surface and for retaining the thread after it is cast off.

19. The combination of a shaft, a disc secured to said shaft and having a cylindrical flange projecting laterally therefrom, said flange being cut away in part to form a thread engaging surface, thread guides located one within and one without said flange, an arm carrying the inner thread guide, and means for supporting said arm whereby when said cut away portion of the flange is over said inner guide, said arm can be raised and the guide positioned for threading.

In testimony whereof, I affix my signature.
JAMES R. MOFFATT.
